SELVAGE TRIMMING MECHANISM

Carl D. Brown, Hopedale, Mass., assignor to
Draper Corporation, Hopedale, Mass., a corpora-
tion of Maine

Application November 7, 1935, Serial No. 48,714

14 Claims. (Cl. 139—266)

The present invention pertains to selvage trimming devices of automatic filling replenishing looms, and has more particular reference to control means therefor.

5 Selvage trimming devices, as provided on the filling replenishing looms in actual use, have been principally of the continuously operating type wherein a thread cutter blade is mounted adjacent the cloth selvage and operated by the lay 10 upon each beat-up of the latter. The formation of filling ends projecting from the cloth selvage is a relatively infrequent occurrence, wherefore most of the operations of the continuously-operating trimming devices are idle, or useless. The 15 problem of eliminating the idle operations of the selvage trimming devices, together with attendant evils, has been long standing and vexatious. The problem is complicated by the fact that, after the replenishing operation, a number of picks of the 20 shuttle may be made before the filling ends have advanced into the range of the selvage trimming devices.

Prior attempts to solve the aforementioned 25 problem have resulted in control devices which are, in turn, controlled from the filling replenishing mechanism. Such devices have usually included a timer, which is necessary if the selvage trimming devices are to remain in operation after the replenishing mechanism has returned to its 30 normal idle position. These prior devices which include a timer are so complicated that they are economically impracticable and have not gone into commercial use. Other such devices, which 35 omit the timer and operate only simultaneously with the replenishing mechanism, are susceptible of use only under limited circumstances as will be obvious.

The present invention provides selvage trimming devices which are normally inoperative, they 40 preferably being held stationary during normal weaving periods, and which are returned to operation through control means which detects and indicates the presence of a filling end projecting from the cloth selvage in position to be cut by 45 said devices. The invention, in one of its aspects, is thus distinguished from the prior art in that according to the invention the operation or non-operation of the selvage trimming devices is determined by the presence or absence of 50 filling ends in position to be cut, rather than by operation of the filling replenishing mechanism.

A further aspect of the present invention per- 55 tains to the position of the control means for the selvage trimming devices. That is, control means for detecting the presence or absence of

a filling end as aforesaid are of necessity quite delicate and could be badly damaged by a trapped shuttle if they were positioned on the loom temple. I have obviated possibility of such damage by providing control devices which may be mounted 5 on the lay where they cannot be engaged by a trapped shuttle.

The preferred embodiment of the present invention includes a thread cutter blade which is carried by the loom temple and which is normally held stationary in inoperative position as by a spring. Means for moving said blade to operative position is comprised of a single element pivotally mounted on the lay for movement to and from blade-moving position. The blade moving ele- 15 ment is controlled by a thread detecting means which may be comprised simply of a feeler wire pivotally mounted on the lay in position to be tilted by a filling end, the feeler, when so tilted, directly engaging the element and moving the 20 latter to operative position. The preferred control devices accordingly consist of but two movable parts both of which are stationary except when called into operation by a filling end.

The said preferred embodiment is illustrated 25 on the accompanying drawings, of which:

Fig. 1 is a plan view of a portion of the right hand side of a loom to which said embodiment has been applied, this view illustrating operation of the parts at the beginning of the first back- 30 ward beat of the lay following filling replenishment;

Fig. 2 is a plan view of a portion of the mechanism of Fig. 1, this view showing the parts at the end of the first forward beat of the lay after 35 filling replenishment;

Fig. 3 is a view partly in elevation and partly in section taken approximately on line 3—3, Fig. 1;

Fig. 4 is a view partly in elevation and partly 40 in section taken approximately on line 4—4, Fig. 2; and

Fig. 5 is a detail, partly in section taken on line 45 5—5, Fig. 2.

The loom shown on the drawings is but frag- 50 mentarily illustrated, it being of conventional design except for the selvage trimming mechanism of the present invention. Of the conventional mechanism, there is shown the lay 1 which is reciprocated forwardly and rearwardly by pit- men, as 2, and which carries a reed 3 and a shuttle box 4, the shuttle 5 being picked along the lay in the usual manner. The particular loom shown is of the bobbin changing variety, it being provided with a conventional hopper 6 55

and transference 7, it being understood that the invention is not limited to use with any particular type of filling replenishing means. The loom is also provided with a temple 8 which is of usual construction except as hereinafter described.

The filling replenishing means shown operates when the shuttle is in the shuttle box 4 and the lay is at its extreme front position. At such time, a filling end *f* extends from the fell of the cloth at the selvage *s* thereof to the shuttle, this position of the parts being not shown on the drawings. Simultaneously with the filling replenishing operation, a suitable parting and clamping device indicated generally at 9 parts and clamps the filling end at a point adjacent the replenishing mechanism. Then, as the lay moves rearwardly the parting device 9 moves forwardly carrying the clamped filling end *f* with it to the position shown by Fig. 1. As the lay continues its rearward movement the shuttle 5 is picked toward the left, Fig. 1, laying in the shed of warps *W* a pick of filling from the newly replenished supply. The end *f'* of this pick of filling extends from the shed to a fixed holder, not shown. The subsequent forward movement of the lay to the position of Fig. 2 results in the pick of filling being beaten into the fell, there being then two filling ends, *f* and *f'*, projecting from the cloth selvage. Such ends must, of course, be cut or trimmed adjacent the cloth selvage.

The selvage trimming devices may be of any suitable form, but are shown as being comprised of a movable cutter blade 10 rockably and slidably mounted in the temple for cooperation with a fixed ledger blade 11. The blade 10 is provided with a depending arm 12, of novel construction, the blades 10 and 11 being otherwise substantially the same as the prior continuously-operating selvage trimming devices. The similarity of the present selvage trimming devices to prior devices of like nature is of importance only as illustrating how existing looms may be converted to embody the selvage trimming mechanism of the present invention without providing new temples.

The selvage trimming mechanism of the present invention comprises, in addition to suitable trimming devices such as those above described, means for normally holding the trimming devices 50 inoperative and for returning the same to operation upon occurrence and through control of a filling end projecting from the cloth selvage in position to be trimmed. In the specific embodiment shown on the drawings, the control and operating means for the movable cutter blade is comprised of a spring, and a detecting means, and a blade moving element.

The spring mentioned is shown on the drawings at 13. It is supported on a stud 14 on the temple and has an arm 15 engaging a stud 16 on the heel 12 of the cutter blade. This spring is similar in construction to that shown in patent to W. I. Stimpson, No. 1,693,942, granted Dec. 4, 1928, except that the present spring is reversely wound and reversely biased, to normally hold the cutter blade 10 in its forward or inoperative position. The spring, it will be noted, holds the cutter blade absolutely stationary, with the arm 12 entirely forward of the path of the lay. As will become apparent, the spring also serves to impart to the blade its cutting stroke.

The thread detecting means shown is comprised of a detector wire 17 which is provided with a portion 18 loosely coiled about a stud 19. The stud 19 is fixed in a part 20 which is adjust-

ably secured to a slotted bracket 21 on the front of the lay. Thus, the detector is pivotally mounted on the lay by means permitting adjustment of the detector along the lay into proper relation to the temple and the cloth selvage. The 5 detector normally points upwardly and forwardly from the stud 19, as shown by Figs. 1 and 3. During the normal operation of the loom the running filling passes to the rear of the detector and accordingly does not engage the latter. Filling ends projecting from the cloth selvage will, however, engage and move the detector as will be hereinafter more fully described.

The blade moving element is comprised of a spring clip 22 pivotally mounted on the stud 19. 15 The clip normally projects downwardly and forwardly from the stud as shown by Fig. 1, the limit of downward movement being determined by a fixed stop lug 25. A downwardly and laterally projecting arm 24 on the detector engages below 20 the lower edge of the clip, the construction being such as to allow a limited lost motion between the detector and clip but to cause the clip to be moved by the detector when the latter is moved clockwise sufficiently from its Fig. 1 position. 25 The spring clip is provided with spaced arms adapted to pass to opposite sides of the arm 12 on the movable thread cutter blade. The arm 12, as shown on Fig. 2, is of triangular cross-section to facilitate the pushing of the clip onto 30 the arm, while the forward ends of the arms of the clip are flared for the same purpose. Inclined shoulders 23, 23 on the clip, when engaged with the arm 12, pull the movable cutter blade rearwardly against the action of spring 13 as the 35 lay moves rearwardly. The shoulders 23, 23 act as cams to spread the arms of the clip and thereby disengage the latter from the cutter blade when the latter has reached the limit of its rearward movement.

The operation is as follows:

During the normal weaving operations, the movable cutter blade 10 is held stationary by spring 13, and the detector 17 and clip 22 remain stationary, or substantially so, all in the position 45 in which they appear on Figs. 1 and 3. It will be apparent that the running filling will at all times be to the rear of the detector. However, any filling ends which project from the cloth selvage are not connected with the shuttle or lay and accordingly are not held rearwardly of the detector. Rather, such ends are usually held forwardly of the lay, as by the clamp 9 or other usual means not herein disclosed. Any such filling end is, of course, comprised of the projecting end of a pick 55 of filling laid in the shed by the shuttle and beaten into the fell by the reed. When the lay moves rearwardly, immediately after having beaten in a pick of filling having a projecting end, the end rides up over the detector as shown by Fig. 3 and 60 thus becomes positioned in front of the detector.

After a filling end becomes positioned in front of the detector, the latter will be engaged and tilted by the former upon the next approach of the lay to its forward position. The parts are so 65 proportioned that the detector will be moved to the position shown on Fig. 4 and in so moving will move the clip 22 to an approximately horizontal position, such movement occurring just before the lay has advanced far enough to bring 70 the clip into contact with the arm 12 of the thread cutter blade. The final increment of forward movement of the lay results in the clip 22 being pushed onto the arm 12 as clearly shown. Then, the lay, in moving rearwardly, pulls the 75

thread cutter blade to its rearward operative position and releases it. As soon as the cutter blade is released the spring 13 pulls it forwardly, cutting the filling end adjacent the cloth selvage and thereafter holding the blade stationary until another filling end is presented thereto when the operation is repeated as above.

Thus, I have provided detecting means which detects the presence of a filling end adjacent the selvage trimming devices, means for normally holding the latter devices stationary in inoperative position, and means for operatively moving the trimming devices only under control of the detecting means. The selvage trimming devices being stationary at all times except when a filling end is presented thereto, the wear incident to continued operation of the prior continuously-operating devices is practically eliminated. Furthermore, the determining of operation or non-operation of the trimming devices in accordance with actual presence or absence of a filling end to be cut eliminates the complex timing devices and other parts of the aforementioned prior mechanisms which were connected to the filling replenishing mechanism.

Having fully disclosed the preferred embodiment of the present invention, I claim:

1. In a filling replenishing loom, the combination of selvage trimming means including a movable filling parting member, means normally holding said member stationary in inoperative position, and means for restoring said member to operation only upon the presentation thereto of a filling end in position to be parted thereby.

2. In a filling replenishing loom, the combination of selvage trimming means including a movable cutter blade, means normally holding said cutter blade stationary in inoperative position, means for detecting the presence of a filling end in position to be cut by said cutter blade, and means controlled by said detecting means for restoring said cutter blade to operation.

3. In a filling replenishing loom, the combination of filling replenishing means, selvage trimming means including a movable cutter blade, means normally holding said cutter blade stationary in inoperative position, means for detecting the formation by said replenishing means of filling ends projecting from the cloth selvage, and means controlled by said detecting means for operatively moving said cutter blade to thereby cut each filling end formed as aforesaid.

4. In a filling replenishing loom, the combination of the lay, selvage trimming means, means normally rendering said selvage trimming means inoperative, means carried by the lay for detecting the presence of a filling end projecting from the cloth selvage, and means controlled by said detecting means for rendering said selvage trimming means operative to part said filling end.

5. In a filling replenishing loom, the combination of the lay, selvage trimming means including a movable cutter blade, means normally holding said cutter blade in inoperative position, means carried by the lay for detecting the presence of a filling end projecting from the cloth selvage in position to be cut by said cutter blade, and means controlled by said detecting means for restoring said cutter blade to operation only when a filling end is present as aforesaid.

6. In a filling replenishing loom, the combination of filling replenishing means, selvage trimming means including a movable cutter blade, means normally holding said cutter blade in inoperative position, means carried by the lay for

detecting the presentation to said selvage trimming means of each filling end formed by said replenishing means, and means controlled by said detecting means for operatively moving said cutter blade to thereby cut each said filling end upon its detection as aforesaid.

7. In a filling replenishing loom, the combination of the lay, filling replenishing means which, upon operation, incidentally forms filling ends projecting from the cloth selvage, selvage trimming means including a movable cutter blade, means normally holding said cutter blade in inoperative position, means carried by the lay for detecting the presence of filling ends adjacent said selvage trimming means, and means controlled by said detecting means for operatively moving said cutter blade only when filling ends are present as aforesaid.

8. In a filling replenishing loom, the combination of the lay, selvage trimming means including a movable cutter blade adjacent the cloth selvage, means carried by the lay for detecting the presence or absence of filling ends projecting from the cloth selvage adjacent said cutter blade, and means controlled by said detecting means for operatively moving said cutter blade when filling ends are present as aforesaid and holding the cutter blade stationary when no such ends are present.

9. In a filling replenishing loom, the combination of the forwardly and rearwardly reciprocating lay, filling replenishing means which, upon operation, incidentally forms filling ends projecting from the cloth selvage, selvage trimming means including a movable cutter blade positioned adjacent the cloth selvage, means normally holding said cutter blade stationary in inoperative position, means for detecting the presence of said filling ends adjacent said cutter blade, and means controlled by said detecting means for operatively moving said cutter blade to cut each said filling end during the first backward beat of the lay following its detection.

10. In a filling replenishing loom, the combination of the reciprocating lay, selvage trimming means including a forwardly and rearwardly movable cutter blade positioned adjacent the cloth selvage, means for detecting the presence of a filling end projecting from the cloth selvage in position to be cut by said cutter blade, a spring comprising means normally holding said cutter blade stationary in its forward position, and means controlled by said detecting means for first moving said cutter blade rearwardly and then releasing the same to control of said spring during the first backward beat of the lay following the detection of said filling end as aforesaid.

11. In a filling replenishing loom, the combination of the lay, a temple having a movable cutter blade thereon, a spring normally holding said cutter blade stationary in inoperative position, a detector finger carried by the lay for detecting the presence of a filling end projecting from the cloth selvage adjacent said cutter blade, and means controlled by said detector finger for operatively moving said cutter blade only when a filling end positioned as aforesaid is detected by said finger.

12. In a filling replenishing loom, the combination of the lay, a temple having a forwardly and rearwardly movable cutter blade mounted in a guideway therein, a spring yieldingly holding said cutter blade stationary in its forward position, a detector finger carried by the lay for detecting the presence of a filling end projecting

from the cloth selvage, and a cutter operating member carried by the lay and controlled by said detector finger for moving said cutter blade rearwardly and then releasing the same upon each 5 occurrence of a filling end as aforesaid.

13. In a filling replenishing loom, the combination of the lay, a temple provided with selvage trimming means including a movable cutter blade, a spring normally yieldingly holding said cutter 10 blade stationary, a cutter operating member mounted on the lay and movable thereon to and from a position where it engages and operatively moves said cutter blade, and a filling end detector carried by the lay and moving said cutter 15 operating member to said cutter operating position only upon occurrence of a filling end projecting from the cloth selvage adjacent said cutter blade.

14. In a filling replenishing loom, the combination of the forwardly and rearwardly reciprocating lay, a temple having a cutter blade movably mounted in a guideway therein, a spring normally yieldingly holding said cutter blade stationary in inoperative position, a cutter operating member mounted on the lay for movement to and from operative position wherein the member engages said cutter blade and operatively moves the latter, said member being normally in inoperative 10 position, and a detector finger carried by the lay and moving said member to operative position only upon the occurrence of a filling end projecting from the cloth selvage adjacent said cutter blade. 15

CARL D. BROWN.
